ANTHONY J. LATELLA, OF NEW YORK, N. Y.

CONVERTIBLE DUMB-BELL.

1,113,791.

Specification of Letters Patent. Patented Oct. 13, 1914.

Application filed February 26, 1914. Serial No. 821,184.

To all whom it may concern:

Be it known that I, ANTHONY J. LATELLA, a citizen of the United States, and a resident of the city of New York, borough of Brooklyn, in the county of Kings and State of New York, have invented a new and Improved Convertible Dumb-Bell, of which the following is a full, clear, and exact description.

10 This invention relates to a dumb-bell of the convertible type, that is to say, it can be converted from an elastic or yielding dumb-bell to one resembling a solid dumb-bell, the weights of which are adjustable, whereby 15 the article is of universal application.

The invention has for its general objects to provide a comparatively simple and inexpensive dumb-bell of the character referred to which is readily changeable from 20 one type to the other and easily adjustable as to weight.

Another object of the invention is the provision of a dumb-bell which is split longitudinally and has a removable middle section to the ends of which are applied adjustable weights, such middle section being removable for permitting the side sections of the handle bars to be used in connection with one or more springs which convert the 30 article from a solid to a yielding handle dumb-bell.

A further object of the invention is the provision of simple, effective and novel means for uniting the parts of the dumb-bell 35 adjustably and detachably together.

With such objects in view, and others which will appear as the description proceeds, the invention comprises various novel features of construction and arrangement of 40 parts which will be set forth with particularity in the following description and claims appended hereto.

In the accompanying drawing, which 45 illustrates one embodiment of the invention and wherein similar characters of reference indicate corresponding parts in all the views, Figure 1 is a plan view of the article shown as a solid bar dumb-bell; Fig. 2 is a perspective view showing the parts of the 50 dumb-bell separated to illustrate the details of construction and with the weights removed; Fig. 3 is a sectional view of one end of the dumb-bell; and Fig. 4 is a perspective view showing the dumb-bell as of 55 the elastic or compressible bar type.

Referring to the drawing, A and B designate the two main sections of the dumb-bell, the middle part of the said sections being rounded to form a grip bar 1 and heads or balls 2 are formed on the ends of the portions 1. Disposed between the sections A and B is a middle section C that in contour is the same as the inner or opposed faces of the sections A and B, so that all three sections co-operate to form a dumb-bell appearance. These sections are secured together by pins or bolts 3 that extend through the head extremities of the sections, the pins having countersunk heads 4 in the section A, and the section B has set 60 screws 5 which are threaded in openings 6 in the end faces of the head extremities 2 of the section B, such set-screws having their inner ends frictionally engaged with the connecting pins 3. The extremities of 65 the middle section C are formed with spindles 7 which serve to receive a plurality of disks or other elements 8 of different sizes and weights, and these disks are held in place by any suitable means, such as a collar 9, on the outer end of each spindle 7, and held in place thereon by a set-screw 10. 70

In Fig. 1 a dumb-bell of maximum weight is shown, but if a lighter dumb-bell is required, some or all of the weights 8 can be 85 taken off. When any weight is taken off the collars 9 will be shifted inwardly so as to clamp the weights tightly against the main body of the dumb-bell and thus prevent looseness and rattling. 90

When the dumb-bell is to be converted from the solid to the yielding type of grip bar, the middle section C is removed entirely from between the sections A and B, and helical compression springs 11 are interposed between the sections A and B, as clearly shown in Fig. 4. The opposed faces of the sections A and B have seats or sockets 12 for receiving the ends of the springs, the outer springs being held in place by the connecting pins or fastenings 3. Obviously the number of springs can be varied according to the resistance desired, the maximum resistance being afforded by the seven springs shown in Fig. 4. The intermediate 95 springs can be removed if a lighter resistance is desired. The pins 3 pass loosely through the ends of the section A, so that when the two sections A and B are compressed together, the section A will slide 100 105 110

on the pins or fastening elements 3. The pins 3 in this form or dumb-bell are longer than the pins required for the type shown in Fig. 1.

- 5 From the foregoing description taken in connection with the accompanying drawing, the advantages of the construction and method of operation will be readily understood by those skilled in the art to which 10 the invention appertains, and while I have described the article which I now consider to be the best embodiment thereof, I desire to have it understood that the article shown is merely illustrative, and that such 15 changes may be made when desired as are within the scope of the appended claims.

Having thus described my invention, I claim as new and desire to secure by Letters Patent:

- 20 1. A dumb-bell divided longitudinally into three sections, adjustable weights on the extremities of the middle section, and means for removably securing the outer sections to the middle section and permitting 25 the outer sections to be detached while the weights remain on the inner section, said outer sections being located between the said weights.
- 30 2. A dumb-bell divided longitudinally into three sections, adjustable weights on the extremities of the middle section, and means for removably securing the outer sections to the middle section and permitting 35 the outer sections to be detached while the weights remain on the inner section, said outer sections being located between the said weights and having seats on their inner surface to receive springs whereby the

dumb-bell is convertible from a solid handle to a resilient handle device.

3. A dumb-bell having a grip portion and weight enlargements at its ends, and said dumb-bell being divisible in two parallel planes at opposite sides of the center to form a central and two outer sections, 45 spindles extending axially from the ends of the middle sections, adjustable weights on the spindles, and means for removably fastening the outer sections to opposite sides of the middle section and permitting the outer sections to be removed while the weights remain on the spindles.

4. A dumb-bell having a grip portion and weight enlargements at its ends, and said dumb-bell being divisible in two parallel planes at opposite sides of the center to form a central and two outer sections, 50 spindles extending axially from the ends of the middle section, adjustable weights on the spindles, and means for removably fastening the outer sections to opposite sides of the middle section and permitting the outer sections to be removed while the weights remain on the spindles, the inner surfaces of the outer sections being formed 55 with seats for receiving springs whereby the dumb-bell can be converted into a solid or yielding grip device.

In testimony whereof I have signed my name to this specification in the presence of 70 two subscribing witnesses.

ANTHONY J. LATELLA.
